UNITED STATES PATENT OFFICE.

WILLIAM P. BETTENDORF, DECEASED, LATE OF BETTENDORF, IOWA, BY JOSEPH W. BETTENDORF, ADMINISTRATOR, OF BETTENDORF, IOWA.

DESIGN FOR A RAILWAY-CAR BODY.

43,078.

Specification for Design.

Patented Oct. 1, 1912.

Application filed July 31, 1912. Serial No. 712,569. Term of patent 14 years.

To all whom it may concern:

Be it known that WILLIAM P. BETTENDORF, deceased, late a citizen of the United States, residing at Bettendorf, in the county of Scott and State of Iowa, did invent a new, original, and ornamental Design for a Railway-Car Body, of which the following is a specification, reference being had to the accompanying drawing, forming a part hereof.

The design relates to the body of freight cars and particularly to the type known as box-cars.

The design consists in constructing a car-body that is pleasing and esthetic in appearance, that avoids the usual hard, sharp lines of the ordinary freight-car construction, and provides graceful and symmetrical proportions and features which are ornate to a more or less extent.

The drawing illustrates the design for railway car-bodies in perspective.

The design consists in forming the side-walls of a box-car with a series of corresponding vertically elongated rectangular panels that are unbroken by openings or cross-members, and are arranged side by side from the ends of the car to the doorway thereof. These panels each have a depressed central portion and a raised edge surrounding the same, the corners of the depressed portions being rounded to break the angularity thereof. The end walls of said

body are each made of several panels each of which has several rectangular depressed portions with rounded corners and raised edges surrounding the same. The eaves of the roof of the car-body are finished with segmentally shaped strips that extend longitudinally from end to end of the car merging into the inclined upper portion of the roof and terminate at ventilating plates at each of the four corners.

Mediate the ends of the car-body, a paneled door closes the door-way and is similar in general design to side-wall panels excepting that it is adorned with a centrally disposed diagonal X-shaped embossment.

The paneled sides of the car-body give the appearance to the car of a border around top and bottom edges of the same, and a series of columns or pilasters connecting the latter in the manner of the Doric style of architecture.

I claim:

The ornamental design for a railway car-body, as shown and described.

Signed at Bettendorf, Scott county, Iowa, this 25th day of July, 1912.

JOSEPH W. BETTENDORF,
Administrator of the estate of William P.
Bettendorf, deceased.
